UNITED STATES PATENT OFFICE.

EUGENE W. VEST, OF TACOMA, WASHINGTON.

WATER-HEATER FOR RANGES, &c.

1,121,693.

Specification of Letters Patent. Patented Dec. 22, 1914.

Application filed December 9, 1912. Serial No. 735,837.

To all whom it may concern:

Be it known that I, EUGENE W. VEST, a citizen of the United States of America, and a resident of the city of Tacoma, in the county of Pierce and State of Washington, have invented certain new and useful Improvements in Water-Heaters for Ranges, &c., of which the following is a specification.

10 My invention has for one of its main objects to provide a water heater of the above type capable of adjustment to obtain a more direct or efficient subjection thereof to the heat.

15 I have shown a preferred embodiment of my invention and in said structure the adjustable chamber serves the function of a valve, controlling a passage for the products escaping to the chimney.

20 In the drawings: Figure 1 is a vertical longitudinal section of a range equipped with my invention, taken on line 1—1 of Fig. 2. Fig. 2 is a fragmentary plan, the cover or top wall of the range being removed. Fig. 3 is a vertical transverse section on line 3—3 of Fig. 2, parts being broken away, Fig. 4 is a fragmentary vertical longitudinal section of the range taken on line 4—4 of Fig. 2. Fig. 5 is a perspective of the water chambers removed, parts being broken away, and Fig. 6 is a vertical section on line 6—6 of Fig. 3, illustrating more particularly the swivel articulated pipe connection between the adjustable water 30 chambers and the boiler.

35 Referring to the drawings by numerals of reference, 1 indicates the fire box, 2 a flue extending therefrom over the oven 3, and 4 a valve controlling a port 4', opening into a vertical flue 5 leading to the chimney, all of which is of well known construction.

40 Reference numeral 6 indicates a water chamber adjustably supported to expose more or less of its wall to the direct action of the heat. In my present construction, said water chamber can be projected into fire-box 1, thereby enabling it to be directly impinged upon by the flames. In conjunction with chamber 6, I prefer to employ a 45 second water chamber 6', and these chambers, whose opposing faces are conveniently corrugated, are normally arranged in superposed relation so as to form one side wall of the fire box. Chamber 6' comprises a hollow body provided at its forward portion with vertical water legs 6'', and between

these legs the forward portion of chamber 6 projects. The rear or outer end portion of chamber 6 is provided with side extensions 7 which during upward adjustment of the chamber abut legs 6'' and thereby limit such adjustment.

45 Reference numeral 8 indicates an inlet water pipe, connected with one end portion of chamber 6', and 9 indicates a pipe establishing communication between chambers 6, 6'. Pipe 9 is swiveled to nipple extensions of the chambers, as shown, to thereby permit of communication being maintained between said chambers at all times, and further acts with suitable levers 10 to steady chamber 6 during its adjustment, as will be apparent. Levers 10 are fulcrumed, as at 10' on chamber 6' and pivotally connected at their upper ends to chamber 6. The lower 50 end portions of these levers are connected by a rod 11 which is engaged in suitable seats 12 of a nut 13, engaged with a screw 14, swiveled in the lower end portion of a compartment 15. This compartment 15 which removably receives chambers 6, 6' projects forwardly from fire box 1 and across the end of the stove. At its rear end portion it opens into a flue 16, leading to flue 5, and provided with a suitable damper 55 17, having an operating rod 23.

60 Reference numeral 17 indicates a guard for preventing passage of the products from fire box 1 over chamber 6 when the latter is in its retracted or lowered position. This guard 17 is pivoted, as at 18, to the upper portion of legs 6'' and slightly overhangs the forward or inner face of chamber 6, whereby it will be swung by the latter during its projection and return to normal position by gravity.

65 Reference numeral 19 indicates an outlet pipe connected with the upper end portions of legs 6'', and 20 indicates an outlet pipe communicating with one of the extensions 7 of chamber 6, which extension 7 is preferably inclined upwardly toward its end, as shown in Fig. 3, for a more perfect circulation of the water therethrough. Pipe 20 projects through a curved slot 20', in the 70 end wall of compartment 15 and through a slide 21 which latter is suitably guided and of such length as to maintain slot 20' closed during adjustment of chamber 6. When but little water is required to be heated, 75 chambers 6, 6' are arranged as shown in full lines in Fig. 1. This permits of the

products escaping to flue 5 either through port 4' or around the oven in the usual manner. With chamber 6 adjusted to the dotted position, it and chamber 6' will have 5 more of their surfaces exposed to the heat, and upon proper adjustment of valve 22 practically all or a portion of the escaping products can be caused to pass between the water chambers to flue 16.

10 Reference numeral 23' indicates a boiler, with which pipe 19 is connected by a T-coupling 24, which latter is provided with a nipple 25. A convenient method of connecting pipe 20 with boiler 23' consists in 15 employing swiveled pipe sections 26, one of which is swiveled to pipe 20 and the other to nipple 25. Pipe 8 is connected with the lower portion of boiler 23', in the usual manner.

20 Having thus described my invention what I claim as new, and desire to secure by Letters Patent of the United States of America, is:—

25 1. In a device of the character described, a water chamber having projecting water legs, a second chamber supported for swinging between the water legs of said first chamber and having side extensions for engagement therewith, and means for swinging 30 said last named chamber.

35 2. In a stove, in combination with the grate, a plurality of superimposed water chambers at one side of said grate, means supporting the upper of said chambers for vertical movement to provide a passage for the heat, means for adjusting said last named chamber, and a guard above said last named chamber for preventing the passage 40 of heat over the chamber and supported for movement by the latter.

45 3. In a stove, a fire box, a pair of water chambers disposed in the path traversed by the products of combustion escaping from said fire box, one of said water chambers being supported for movement toward and from the other, and means for adjusting said movable water chamber from the other to thereby provide a passage-way between 50 said chambers for the escaping products of combustion.

55 4. In a stove, a fire box, a flue having communication with said fire box, a pair of water chambers arranged in superposed relation above and at the side of the grate of said fire box and in the path of communication between the latter and said flue, one of said water chambers being adjustable, and means for spacing said last named water chamber from the other, whereby the products of combustion can pass therebetween to 60 said flue.

65 5. In a stove, a fire box, a flue having communication with said fire box, a pair of water chambers arranged in superposed relation above and at the side of the grate of

said fire box and in the path of communication between the latter and said flue, one of said water chambers being adjustable, and means for bodily moving said last named water chamber into said fire box to thereby obtain a spacing of one water chamber relatively to the other. 70

6. In a stove, a fire box, a flue connected to communicate with said fire box directly through one vertical side thereof, a water chamber adjustably supported in the last named side of said fire box in the path for the products of combustion to act as a valve for controlling the latter, and means for adjusting said water chamber. 80

7. In a stove, a fire box, a flue connected with one side of said fire box, a water chamber adjustably mounted at the last named side of said fire box and serving to block the passage of the products of combustion to said flue, and means for advancing said water chamber into said fire box to thereby open communication between the latter and said flue. 85

8. In a stove, a fire box, a pair of water chambers arranged above the grate of said fire box, one of said water chambers being adjustably mounted whereby it can be spaced from the other, means for adjusting said last named water chamber from the other, and a flue connected to have communication with said fire box through the space between said water chambers. 90

9. In a stove, a fire box, a pair of water chambers arranged one on the other above the grate of said fire box, one of said water chambers being adjustably mounted whereby it can be spaced from the other and projected into said fire box, means for adjusting said last named water chamber from the other, and a flue connected to have communication with said fire box through the space between said water chambers. 100

10. In a stove, in combination with the grate, a plurality of water chambers normally resting one on the other and forming one wall of the fire box, means for elevating one of said chambers bodily, and a flue connected to have communication with the fire box through the space between said water chambers when the last named chamber thereof is elevated. 110

11. In a stove, in combination with the grate, a plurality of water chambers normally resting one on the other and forming one wall of the fire box, means for bodily elevating and projecting one of said chambers over said grate, and a flue connected to have communication with the fire box through the space between said water chambers when the last named chamber thereof is elevated. 120

12. In a stove, a fire box, a flue having communication therewith, and a water heating chamber normally closing the flue and 130

adapted for projection into the fire-box to open the flue.

13. In a stove having a slot in the wall thereof, a fire-box, a slide for closing the wall slot, a water heating chamber, a conducting pipe connected to the heating chamber and passing through the slide, means for advancing and simultaneously elevating the heating chamber toward the fire-box, and a

connection between said pipe and slide to permit of relative movement thereof during movement of the heating chamber.

Signed at Seattle, Washington, this 20th day of November 1912.
